DEVICE FOR VIEWING OIL WELL BORE HOLE

James Moon, Santa Ana, and Robert C. Crooke,
Temple City, Calif.

Application February 3, 1956, Serial No. 563,344

25 Claims. (Cl. 178—6.8)

This invention relates to novel apparatus for visually observing the condition of well bores and is particularly concerned with a device of this character embodying a closed circuit television system for viewing from a remote distance the inside of an oil well bore or casing.

Devices have heretofore been developed for subterranean and submarine photography, but such devices have not generally proved very successful for observing a well bore, or well casings, well drilling tools and the like in a well bore, mostly due to the difficult conditions of high pressures and temperatures encountered at great depths in an oil well bore, and the drilling mud, oil and muddy water common to such an environment. Particularly, while a device which would permit proper visual inspection of a well bore hole from the well surface would be of considerable advantage to the industry, no commercially satisfactory device known to applicants has heretofore been developed which enables visualization of a well bore from remote distances while the tool is in the well bore.

One object of the invention is to design a device permitting viewing of the inside of a well bore.

Another object is the design of such a device incorporating a camera and preferably a television system for viewing a well bore from a station at the surface of the well.

A still further object is to design a tool which can be submerged in an oil well bore at great depths and in contact with well bore fluids, yet which permits pictorial viewing of the well bore even in the presence of and during passage of the tool through relatively opaque liquids in the well bore. By the term "pictorial viewing" is meant the taking of photographs by means of a film-containing camera, or the use of a television camera for direct transmission of a picture to a station at the surface of the well bore.

Another object is the design of a tool for pictorially viewing a well bore, which includes camera means and has provision for cooling to maintain the camera means at a proper operating temperature under high well bore temperatures, and for efficiently scanning and lighting the portion of the well bore under observation.

Yet another object is the provision of a tool for viewing a well bore, which includes camera means and a protective lens, in conjunction with a closure means and lens washing means, the closure means being adapted to be opened and closed a plurality of times to permit washing of the lens at selected intervals while the tool is in the well bore, so that a number of pictures may be obtained at various locations within the well bore without removal of the tool from the bore.

A particular object is to provide a device for remote pictorial visualization of an oil well bore hole, said device being constructed of a combination of readily available structural, optical, and television receiving and transmitting components, which can be assembled to form a compact, rugged, yet reliable instrument for the above purpose, able to withstand and operate under the unusual environmental conditions, including the high pressures, temperatures and opaque and viscous liquids generally encountered in oil well bores.

2

Other objects and advantages will appear hereinafter.

The device of the invention is specially designed for and embodies camera means preferably as a component of a closed circuit television system which is of standard commercial type except that the television package embodying all of the electronic and optical components thereof, is altered in shape, e.g. to an elongated cylindrical form, to permit its being housed within the relatively slender elongated case of our instrument. In order for the electronic and optical components of the system to function properly, provision is made to isolate these components from the environmental conditions, e.g. the high temperatures and pressures, found in oil well bores. Particularly, the instrument hereof is designed to withstand hydrostatic well pressures in excess of 6,000 p.s.i. and ambient wall temperatures, e.g. up to and above 375° F., and means are provided to protect the viewing lens from becoming coated with fluid which render it optically opaque, and to wash the viewing lens free of any dirt or soil which is deposited thereon. The system is also provided with means for supplying adequate illumination to the subject matter which is to be viewed, and the instrument also embodies means for maintaining the sensitive electronic components of the television system sufficiently cool to insure its efficient operation.

In one form of the invention the outer case of the tool or instrument is of cylindrical shape and is composed of several components which are joined together for ease of manufacture and assembly. At the lower end 30 of the cylinder case (the viewing end) there is provided a closure means, preferably a flexible diaphragm which can be opened and closed, and above this is positioned a protective viewing lens which closes off the interior of the case from well bore fluids, and through which the television camera receives light. The protective lens is sufficiently thick to withstand the pressure of the well bore fluids, and means is provided to afford a pressure seal between the lens and case. The purpose of the closure or the diaphragm is to protect the protective viewing lens when the unit is passing through fluids which would coat the outer surface of the protective lens. Between the diaphragm and the protective lens is a chamber into which a lens washing fluid can be forced by means of a conduit communicating with the chamber, said fluid being discharged directly below and closely adjacent the surface of the lens.

Immediately above the protective lens, and surrounding the camera lens is a light source preferably in the shape of a doughnut. Above this and centered in the 50 instrument case is the packaged electronic equipment, including the camera, of the television system. The annular space between the electronic equipment housing and the outer shell of the instrument case is filled with a cooling medium such as a refrigerated eutectic material 55 which will absorb the heat generated in the system and that received from the oil well bore.

Above the electronic equipment is a pressure equalized hydraulic system including a cylinder, piston, porting, and drive motor, all of which operate the diaphragm 60 and the protective lens washing system. Above the drive motor is a balanced reservoir which supplies makeup fluid to the hydraulic system for use in the protective lens washing system.

65 The hydraulic system comprises a pressure cylinder and double acting piston. The piston divides the cylinder into two parts, the lower part being connected by a conduit to the flexible diaphragm. As the piston is moved downward the fluid is forced out of a port and through the conduit, causing the flexible diaphragm to expand. When the direction of motion of the piston is reversed, the fluid returns to the resulting low pressure

area below the piston. The upper portion of the hydraulic cylinder is connected through piping to a check valve and thence through a second conduit to the protective lens washing chamber. The upper portion of the hydraulic cylinder is also connected through piping and a check valve to the bottom portion of the reservoir, which contains a freely floating piston with the space above the piston vented to the well bore fluid and pressure. As the hydraulic piston is moved upwards the washing fluid is forced out the top of the hydraulic cylinder through the protective lens washing system. The washing fluid cannot re-enter the reservoir due to the presence of the last mentioned check valve. When the hydraulic piston is displaced downward again, fluid enters the top portion of the hydraulic cylinder from the reservoir. Well bore fluid cannot be taken from below the protective lens into the hydraulic cylinder through the wash fluid piping due to the presence of the check valve in such piping. The hydraulic piston is moved by means of a threaded piston rod running in a drive nut which is connected to a motor.

At the top of the instrument is a packing system through which an electrical cable enters the case, and an arrangement for tying the cable armor onto the case for supporting the instrument and for raising and lowering it in a well bore. The electrical cable carries the necessary electrical conductors to supply energy to the various electrical or electronic components of the system, i.e. the lamp, television circuit and motor. The cable is covered on the outside with armor wire which will carry the load and protect the cable.

The entire inside of the tool is charged with an inert gas at slightly more than atmospheric pressure. The use of the inert gas avoids the problems associated with air when temperature changes take place, due to water vapor in the air.

From the above it is seen that on actuation of the television system having a viewing station at the well surface, a picture of the well bore at any level of the bore can be obtained and the condition of the bore thus ascertained. If the protective viewing lens becomes covered with mud or soil particles so that the picture is unclear, the motor can be actuated to force cleaning fluid preferably of transparent type, from the hydraulic cylinder and over the lens to clear it. Should the instrument pass through sticky or opaque fluids, the motor can be actuated in the opposite direction to force fluid into the protective diaphragm to close off well bore fluids from contact with the protective viewing lens, and when the well bore is to be viewed under these conditions, the diaphragm can be opened and the transparent cleaning fluid located in the space in front of the protective viewing lens permits viewing of a portion of the bore through the transparent liquid.

In the embodiment of the invention noted above, the system is arranged to enable the well bore directly below the instrument to be viewed, while in another embodiment, described more fully hereinafter, the system is especially arranged to enable viewing of the sides of a well bore.

The invention will be more readily understood from the following description of certain preferred embodiments taken in connection with the accompanying drawings wherein:

Fig. 32 is a schematic diagram of a typical commercial closed circuit television system which can be employed in our device.

Referring to Fig. 1, the device comprises an elongated cylindrical housing 33 made up of a series of cylindrical sections threadably joined to each other, the housing having positioned in the lower end thereof an optical viewing system 34, including a protective lens 35 and a lens protective diaphragm 37 (see Fig. 2), and a television camera and transmitting system 36, these components cooperating in the manner described below for viewing a bore hole. Within housing 33 and located above the television system 36 is a hydraulic system 38 which serves to provide fluid for and to actuate a washing system for

the protective lens, and also to operate the protective diaphragm 37. A motor 40 and associated linking mechanism 41 between the motor and hydraulic system 38, are located within housing 33 above the hydraulic system 38 for operating the latter, and in the upper portion

of the device above the motor is positioned a reservoir 42 which supplies makeup fluid to the hydraulic system 38. The device is suspended on an armored cable 44 for lowering and raising the device in a well bore hole, the cable extending out through the top of the device and containing electrical leads for purposes pointed out more fully below.

Turning now particularly to Fig. 2 at the lower end of the device is a closure ring assembly 46 made up of a cylindrical shell 48 the outside surface of which is grooved at 50. Through the shell and passing into the groove are several holes 52 (see also Fig. 8). To the inner surface of the shell 48 is vulcanized adjacent its upper and lower edges 55 the cylindrical flexible diaphragm 37 made of a suitable elastic material such as rubber. The diaphragm 37 when deflated is shown in

Fig. 2, with a small annular space 71 between the shell 48 and the diaphragm, but when inflated by means of pressure fluid, distends into the chamber 72, forming a doughnut-shaped member closed at its center, as seen in Fig. 3, thus closing off the space or chamber 72 between the diaphragm 37 and lens 35. The closure ring assembly 46, including diaphragm 37, is slipped inside of a retainer ring 58 so that assembly 46 fits at its upper end inside of an annular slot 54 provided in the inner surface of retainer ring 58. The lower end of ring 58 has an internal thread 60 into which a retainer nut 62 can be screwed for the purpose of securely holding the closure ring assembly 46 in the retainer ring 58, the nut 62 having an annular groove 57 to accommodate the lower end of shell 48 and diaphragm 37 connected thereto. The retainer ring 58 is supplied at its upper end with an external thread system, such as the two step thread 64 shown, for the purpose of joining 58 to the lamp housing body portion 66.

The retainer ring 58 is drilled with two bores 68 and 70. One of the bores 68 is directed radially inward at 69 and is the outlet for the protective lens wash fluid, communicating with chamber 72 defined by retainer ring 58, diaphragm 37 and the front of the protective lens 35. While only one discharge outlet 69 is shown, a plurality of such outlets can be provided about the periphery and adjacent the lower surface 35' of lens 35. The other bore 70 is drilled so that it registers with the groove 56 in the shell 48 and is for the purpose of introducing fluid into the space 71 between the diaphragm and shell 48 of ring 46, to inflate the flexible diaphragm. Both of these bores or conduits terminate at their upper ends in the blocked annulus 74 at the step in the thread system 64 (see also Fig. 31). This provides a separate arcuate channel 75 which communicates with bore 68, and a separate arcuate channel 76 communicating with bore 70. The annulus 74 is blocked in the above manner by flats 77 at diametrically opposite portions of annulus 74, in order to prevent the mixing of the fluids in the lens washing and diaphragm actuating systems, as will be seen more clearly hereinafter. The retainer ring 58 is provided with a shoulder 78 which, along with a gasket 100, holds the protective lens 35 in position in the lamp housing body 66.

The protective lens 35 is designed thick enough to withstand the external pressure against its front surface 35'. The surface 35' of the lens has a convex shape for the purpose of facilitating the washing action of the lens washing fluid. The lens is made up of two pieces of suitable glass, a central tapered portion 82 in the form of a truncated cone, and an outer hollow cylindrical portion 84 internally tapered at 83 to fit the taper of outer portion 82 (see Figs. 9 and 10). The two portions 82 and 84 of the lens 35 are matingly cemented together by means of a black opaque cement 85. This arrangement of the protective lens 35 eliminates the tendency towards backscattering of light to the optical lens of the television system when a film of particles is deposited on the front surface 35' protective lens 35.

The lamp housing body 66 is threaded at both ends 86 and 88. The lower end makes up with the retainer ring 58, and the upper end makes up with the body shell 90 surrounding the housing 92 containing a television camera indicated by the numeral 93 and the electronic television components. A cylindrical housing 94 containing a conventional television camera lens (not shown) is axially connected to the lower end of television housing 92, in axial alignment with lens 35, and adapted to receive light passing through the central portion 82 only of lens 35.

The lamp housing body 66 contains a lamp housing 95 in which is formed an annular recess 96 in which a doughnut-shaped lamp 98 is positioned by means of fasteners 101 connecting the lamp to a bracket 103 attached to the lamp housing (see Fig. 6). The lamp 98 is of doughnut

shape so that the maximum uniform illumination possible may be obtained in the smallest space. It is noted that lamp 98 is positioned directly opposite the outer portion 84 of lens 35. In this manner light is directed from the lamp through outer portion 84 of the lens into the well bore beyond the lower end of ring 46, as indicated by arrows A in Fig. 2, and the light is reflected back from the well bore through the central portion 82 of lens 35 into the camera lens-containing cylinder 94 of the television system, as indicated by arrows B in Fig. 2. The opaque film 85 prevents passage of light from outer lens portion 84 of lens 35 directly into the center lens portion 82 thereof.

An O ring groove 99 is formed in lamp housing 66, and into this groove is positioned the O ring 100 for the purpose of forming a pressure tight seal between the protective lens 35 and the lamp housing body 66. The lamp housing body 66 also contains two circular seats 102 and 104 against which the protective lens 35 is held by the retainer ring 58. A pair of bores 68' and 70' are drilled into lamp body 66, these bores corresponding to the bores 68 and 70, respectively, drilled in retainer ring 58. The lower ends of bores 68' and 70' terminate at the blocked annulus 74 between the step threads 64, and communicate with channels 75 and 76, respectively. Hence, bores 68 and 68' and channel 75 form a continuous conduit 106 and bores 70, 70' and channel 76 forms a separate continuous conduit 108. The upper ends of bores 68' and 70' terminate in drilled and threaded holes 109 and 110 which take the elbows 112 and 114. A diaphragm closure tube 116 is fastened to the elbow 114 and a lens washing tube 115 is fastened to the elbow 112.

The upper end of the lamp housing body 66 is provided with a shoulder 118 upon which a stop ring 120 is seated. Stop ring 120 is provided for the purpose of supporting the television camera and electronics package retained in housing 92. Ring 120 is drilled with holes which allow for passage of the lamp wires 122, the diaphragm closure tube 116 and the lens washing tube 115. The body shell 90 is provided with threads 124 and 126 at opposite ends. The lower thread 124 makes up with the lamp housing body 66, and the upper thread 126 makes up with a body shell 128.

The television camera and electronics case 92, including camera lens holder 94, contains all of the necessary electronic and optical components of a complete closed circuit "vidicon" television system. The television system employed, including the transmitting and receiving components thereof, is of a conventional commercial type available from sources such as Radio Corporation of America. Fig. 32 shows for purposes of illustration a schematic diagram of the main components of a typical television system which we can employ in our device. This system per se is not claimed as a part of our invention. All of the components illustrated in Fig. 32 are contained within the electronics case 92 of Fig. 2, except the viewing or picture tube 123 and an outside power supply 125, which are located at the surface and connected to the electronics case 92 by means of leads 127. This system is shown on page 2 of the Radio Corporation of America brochure for "Model ITV-6, Industrial Television Equipment." The diameter of the electronic shell or housing 92 is maintained as small as possible in keeping with good electronic design. In any case, the diameter of the electronic package 92 is kept smaller than the inside diameter of the outer body shell 90.

The space 129 between the television camera and electronics case 92, and the body shell 90 is substantially filled with a pair of semi-cylindrical containers 130 (see also Fig. 5) which are made of a suitable material such as polyethylene plastic. The space between adjacent and portions of containers 130 is employed for the passage of the hydraulic lines 115 and 116 and lamp

wires 122. The containers 130 are filled with a commercially available and suitable coolant, preferably a eutectic substance, e.g. one composed of a mixture of calcium chloride, starch, and water. The heat capacity and volume of the eutectic material is so chosen that the complete tool when cooled to -20° F. at the start of any operation will only reach a temperature of 120° F. at the photosensitive surface of the vidicon tube after an exposure of four hours to an outside ambient temperature of 375° F.

The longitudinal motion of the television camera and electronics package 92 is limited at the upper end by the keeper rings 132 and 134. These keeper rings are held against the case 92 by the abutting lower end 136 of the upper adjacent body shell 128.

The body shell 128 (see Figs. 2 and 11) is provided with a right hand thread system 136 on its lower end, and a left hand thread system 137 on its other end. This permits the lower sections 128, 90, 66 and 58 of the system to be joined to the upper body shell 138 without relative rotation of either section 90 or 138 at opposite ends of section 128.

The body shell 138 is likewise provided with a thread system on each end, the lower threads 140 for making up with the body shell 128, the upper threads 142 for making up with body shell 144 (see also Fig. 14). The body shell 138 is drilled and tapped to take the dog pointed socket head set screw 146 which holds a sleeve 148 positioned in body shell 138 from moving.

A base ring 150 (see Fig. 11) is provided as an anchor plate for the hydraulic system indicated generally by numeral 38. The base ring 150 is held in place by the shoulder 154 provided on the body shell 128, and is prevented from rotating by means of a serrated edge 156 thereon (see Fig. 13). Base ring 150 is drilled with clearance holes to receive the keeper bolts 158, for the elbow 160 which is connected to the hydraulic diaphragm closure line 116, for the electrical cable 44 carrying lamp wires 122 and television leads 127 (see also Fig. 2), and for the hydraulic wash line 115. The keeper bolts 158 are for the purpose of anchoring the cylinder base 164 to the base ring 150.

The cylinder base 164 is threaded internally at 166 and is provided with an O ring groove 168 to accommodate O ring 170. The cylinder 172 is screwed into the base 164 making a pressure tight seal with O ring 170. Cylinder base 164 has a port 174 for discharging fluid via line 116 to the flexible diaphragm 37. The hydraulic cylinder 172 is provided with a piston 178 which makes a pressure tight seal with the cylinder walls by means of the cup ring seals 180. The arrangement is such that the seal is maintained when the piston moves in either direction. The upper end of the cylinder 172 is mated by a thread system 182 and O ring seal 184 to cylinder top member 186.

The cylinder top 186 is drilled and provided with packing 188 to take the piston rod 190 which is connected to the piston 178 by means of the piston rod nut 192. The cylinder top 186 is also drilled to provide a hydraulic port 194 to which the T fitting 196 is connected. One arm 195 of the T 196 is connected to the lens washing tube 115 which contains a ball check valve 198 (see Fig. 2) permitting flow only in a direction through wash line 115 away from the T toward the lens washing bores 68' and 68. The other arm 200 of the T 196 is connected to a hydraulic charging line 202 which contains a ball check valve 204 (see Fig. 14), and is connected to the lower end of the reservoir 42. The check valve 204 permits fluid flow only from the reservoir to the hydraulic cylinder 172.

The hydraulic cylinder assembly 38 is held in place by the ring 206 and the sleeve 148, which is forced up against the keeper ring 208 (see Fig. 14). The sleeve 148 which is restrained from rotating by set screw 146, has a fork member 209 thereon which receives the upper

end of the piston rod 190. Sleeve 148 has a tendency to rotate because fork 209 on the sleeve functions to restrain the rotational motion of the piston rod 190 in the manner described below. The piston rod 190 above the hydraulic cylinder 38 has a length of flats indicated at 210 and a length of threads 212. The length of flats and threads are each at least equal to that of the travel of piston 178, permitting piston 178 to travel from the bottom to the top of hydraulic cylinder 38. The section of flats 210 having a polygonal cross section passes through a mating polygonal aperture 211 (see Fig. 16) in the fork 209, which limits the piston rod 190 and piston 178 to reciprocal movement only when the motor drive nut 214 engaging the threaded portion 212 of the piston rod 190 is rotated.

An electric motor and gear unit indicated generally by numeral 40 fits inside of the body shell 144, the unit being fixed to an anchor plate 218, welded at 221 inside the shell 144 near the top thereof, by means of retainer bolts 220. Motor shaft 217 passes through the keeper ring 208, and is connected by means of taper bolts 219 to the drive nut 214. The anchor plate 218 is drilled to provide openings for the motor electric power lines 222, which are taken out of the main cable 44, at the junction box 224. The main cable 44 carries the lamp leads 122, the television leads 127 and the motor leads 222, said leads being contained in separate control cables 122', 127' and 222', respectively. Access through the anchor plate 218 is also provided for the main cable 44 and hydraulic charging line 202. The lower end of the motor and gear units are positioned by the keeper ring 208 and the keeper sleeve 148. The body shell 144 is joined to the body shell 226 (see also Fig. 18) by means of the make-up shell 225 which has a right hand and left hand thread system 228 and 230 to permit shell 144 to be connected to shell 226 without relative rotation.

The motor and gear unit 40 are connected by leads 222 to a cycle timer (not shown) at a station at the surface of the well, said timer operating to cut the motor 40 when the hydraulic piston 178 reaches the top or bottom of hydraulic cylinder 38. Such timer is also operative to cause a reciprocating motion of piston 178 through a relatively small distance in the cylinder 38, for a purpose noted hereinafter. Cycle timers of this type are well known and commercially available. A typical cycle timer which can be used in the invention is the model type 520 cycle timer marketed by the P. W. Cramer Company of Centerbrook, Connecticut, and shown in its bulletin P.B. 510.

Referring now to Fig. 18, cylindrical reservoir body 42 is closed on the lower end by the reservoir base bottom 234 and on the top by the reservoir top member 236. These end members are internally threaded at 238 to mate with external threads at the ends of the reservoir cylinder 42. O ring seals 240 are positioned between the end members 234 and 236, and the opposite ends of cylinder 42. Inside the reservoir 42 is a freely moving piston 242. This piston carries ring seals 243 to make a pressure tight seal with the walls of cylinder 42, and divides the reservoir into two chambers with the protective lens wash fluid maintained in chamber 244 below the piston 242. The chamber 246 above the piston is filled with the well bore fluid at ambient pressure by means of the vent plug 248 communicating with chamber 246 via conduit 250.

The reservoir cylinder ends 234 and 236 carry trunnions 252 and 254 which are axially bored to match bores formed in cylinder ends 234 and 236, and forming conduits 256 and 250. The lower trunnion 252 fits into a recess 258 formed in a journal bearing 260 integral with the body shell 226, and an O ring seal 268 is provided between the trunnion 252 and bearing 260. The lower journal bearing is bored at 261 to match the conduit 256. This gives a pressure tight joint which is rotatable for purposes of making up the tool, and which provides

fluid communication between the lower chamber 244 of the reservoir and the fittings 263 and 265 (see Fig. 14) of the hydraulic charging line 202. Also provided in the lower journal bearing 260 is a cross connection 267 from bore 261 to an outside fill-up plug 269 to permit charging of the hydraulic washing fluid to the lower chamber of reservoir 42. The trunnion 254 on the reservoir top member 236 fits into a recess 262 formed in a journal bearing 264 integral with the upper adjacent body shell 266, and an O ring seal 270 is provided between the trunnion 254 and the bearing 264. This journal bearing is drilled at 271 to match the trunnion port 272, forming conduit 250 which terminates at one end with the vent plug 248 and at its other end with the upper chamber 246 of the reservoir. Body shells 226 and 266 are joined by means of a thread system indicated at 274.

Referring to Fig. 22, the body shell 266, while furnishing journal 264 for the reservoir and an inert gas charging plug 276, functions chiefly for the purpose of sealing and tying off the armored electrical cable 44, carrying motor leads 222, television leads 127 and lamp leads 122. The cable 44 enters the tool at the extreme top, where it is passed through a clearance hole 278 in the head 280 of the instrument case. The outer armor wire 282 around the cable is peeled back at 284 and cut off so that the required length of unarmored cable can be run down through the tool to its juncture with an upper housing 286 (see Fig. 2) connected to television case 92. The cut off ends 288 of the armor are bent back so that they will fit in behind an armor wire retaining slip 290, which is wedged and locked in place by means of a locking nut 291 which mates with threads 287 on a depending cylinder portion 289 of head 280. Below the armor, or load transfer point, the unarmored cable passes through a high pressure packing gland system 292 consisting of chevron ring packing 293, a lantern ring 294 interposed between layers of the chevron ring packing, a standard packing ring 295 and a keeper nut 296 mating with the threads 297 on a flange 297' extending upwardly from a housing 298 integral with body shell 266, and which contains an annular recess 299 which carries the chevron packing 293 and the lantern ring 294.

Operation of the device described above is as follows:

The retainer nut 62 at the lower end of the tool is removed and the closure ring assembly 46 including the diaphragm 37 is withdrawn. The motor 40 is actuated to cause the piston 178 to move to the upper end of hydraulic cylinder 38, following which the entire tool is inverted and a fluid, which may be the same as the washing fluid described below or any other suitable fluid, is introduced into the end of bore 70 adjacent chamber 72, the fluid being conducted by gravity via bore 70, channel 76, bore 70' and line 116 into the chamber 301 of hydraulic cylinder 38. The closure ring assembly 46 is then inserted into retainer ring 58 and the nut 62 is screwed into position to lock the closure ring assembly 46 in the lower end of the tool. The fluid in the lower chamber 301 of the hydraulic cylinder is now sealed therein, since this chamber forms a closed fluid system with the diaphragm closure line 116, and space 71 between diaphragm 37 and the adjacent shell 48.

The amount of fluid thus introduced in the closed system including the lower chamber 301 of the hydraulic cylinder 38, line 116, bores 70 and 70', and space 71, is such that when piston 178 is in its lowermost position in cylinder 38, as viewed in Fig. 11, the diaphragm 37 will be inflated and expanded to its fully closed position as shown in Fig. 3, and when the piston 178 is in its uppermost position at the top of cylinder 38 the diaphragm 37 will be substantially open as shown in Fig. 2.

With the instrument still inverted, a washing fluid, which may be an alcohol, a glycol, a hydrocarbon or chlorinated hydrocarbon solvent, water, or any other suitable preferably transparent lens washing fluid, is introduced into the lower chamber 244 of the reservoir

cylinder 42. Charging of the tool with washing fluid is accomplished by removing plug 269 and introducing the fluid into conduits 267 and 256, causing the piston 242 in reservoir cylinder 42 to move to the top of said cylinder, as viewed in Fig. 18.

The tool is then positioned on its side, that is, horizontally, and additional washing fluid is introduced through conduit 267 causing such fluid to pass through line 202 and the check valve 204 therein, through T 196 and bore 194 to the upper end of the hydraulic cylinder 38. During this procedure the tool is gently rocked back and forth to purge any air in line 202 through the conduit 267 and the filling opening 269. When filling of the instrument with washing fluid has been accomplished the plug 269 is screwed into position as seen in Fig. 18.

It will be noted that during the filling operation described above, washing fluid rapidly passes from the filling conduit 267 through line 202 and through the check valve 204 to the hydraulic cylinder 38, since check valve 204 is designed so that only a relatively small fluid pressure is required for passage of liquid therethrough in a downward direction as viewed in Fig. 14. However, it will be noted that during the filling operation while the washing fluid fills line 115 between T 196 and the check valve 198, the fluid does not pass the latter check valve since this valve is spring loaded and preferably designed to permit passage of fluid downwardly as seen in Fig. 2, at a fluid pressure of 25 p.s.i. or greater.

The instrument is then lowered into the bore hole. Preferably, at the commencement of lowering of the tool into the bore, or prior thereto, the motor 40 is actuated to cause hydraulic piston 178 to travel to the bottom of the cylinder 38 as viewed in Fig. 11. This forces hydraulic fluid out of the lower chamber 301 of the hydraulic cylinder, through elbow 160, line 116, bores 70' and 70, and holes 52, into the space 71 between the diaphragm 37 and the shell 48. This causes the diaphragm to expand until it closes off chamber 72 from the bore hole below the diaphragm, as seen in Fig. 3. During movement of piston 178 downward in cylinder 38, the pressure in the upper chamber 300 of the hydraulic cylinder drops, causing piston 242 in the reservoir cylinder 42 to move downward and to force fluid into the upper chamber 300 of the hydraulic cylinder, via line 202 and valve 204 as described above, since the upper chamber 246 of the reservoir is at a higher pressure corresponding to the hydrostatic or well bore pressure due to the presence of vent plug 248.

When it is desired to view the bore hole at any particular depth, the instrument is lowered to this point, and the circuits to the lamp and television power sources are actuated from a station at the surface of the bore, at which station the television picture tube which receives the image of the well bore to be inspected, is also located. The depth can be determined by any known or convenient means, e.g. measuring the length of cable lowered. If the fluid through which the tool is passed is relatively clear fluid, the diaphragm 37 can be opened for purpose of viewing the well bore beneath, by actuating the circuit to the motor 40 to cause the drive nut 214 to rotate in a direction to force piston rod 190 and the piston 178 upward in hydraulic cylinder 38.

This operation simultaneously forces washing fluid out of the chamber 300 of the hydraulic cylinder, through bore 194, T 196, T arm 195, tube 115; check valve 198, and bores 68 and 68', into the chamber 72, in which the fluid is introduced from the inclined end 69 of bore 68, which directs the fluid across the outer surface 35' of the protective lens 35. It is noted that washing fluid cannot circulate from upper chamber 300 of the hydraulic cylinder back through line 202 to the reservoir 42, due to the check valve 204; preventing flow in this direction. The fluid in chamber 72 below lens 35, in addition to cleaning the surface 35' thereof, also serves as a trans-

parent medium through which the desired area of the well bore can be viewed, and such fluid is prevented from returning from chamber 72 through line 115 back to the upper chamber 300 of the hydraulic cylinder, due to the action of check valve 198, which blocks flow in this direction.

Should the surface 35' of lens 35 become covered with oil, mud particles or other opaque material, resulting from passage of the instrument through opaque, murky or oily masses of liquid in the well bore, thus preventing a clear picture of the bore, or if the fluid in the well bore at which the picture is to be taken is opaque, instead of opening the diaphragm 37 relatively rapidly as described above, motor 40 is actuated to lift piston 178 in the hydraulic cylinder 38 a relatively short distance, say about 2 inches off the bottom of cylinder 38. The piston is then reciprocated up and down over a distance of about 1 inch to open the diaphragm slightly and then partially close the same, to produce a nozzle effect and force washing fluid in short jets into the space 72 below the lens while permitting opaque fluid in space 72 to be discharged through the opening in the diaphragm into the well bore below, thus eventually forming a clear bubble of liquid in space 72 between the diaphragm and lens 35. Thereafter the motor is actuated to force the hydraulic piston 178 to the top of the cylinder to completely open the diaphragm 37 to permit viewing of the well bore below through the bubble of washing liquid in space 72. Particularly if the washing fluid is lighter than the fluid in the well bore, the bubble of washing fluid will be maintained in space 72 for a period sufficient to permit proper viewing of the well bore at the desired location therein. After viewing the well bore, the motor can be actuated to force piston 178 downward to the bottom of cylinder 38, thus again closing the diaphragm 37.

The above described operations can be accomplished by means of a cycle timer, mentioned above, in series with the motor 40. The timer operates on a time relay such that at the time of reversal of the motor when piston 178 reaches the bottom or the top of the hydraulic cylinder, the motor will be cut off to prevent further movement of the piston. Also the cycle timer can be set so that starting at any position of the piston 178 in the cylinder 38, say about 2 inches from the bottom of the cylinder, the cycle timer will stop the motion of the piston after it has traveled a certain distance, say downward about 1 inch to partly close the diaphragm 37, and then will reverse the motor to permit the piston to travel in the opposite direction, e.g. upward, to its initial starting position, to partially open the diaphragm, the cycle timer actuating the motor to repeat this operation so as to reciprocate piston 178 through a small predetermined distance above the bottom of cylinder 38, thus repeatedly partially opening and closing the diaphragm to produce a small but variable nozzle opening. Simultaneously with the opening and closing of the diaphragm this motion of piston 178 will cause a jetting action of the washing fluid through bore 69 into space 72 below the lens 35, displacing the fluid therein with clear fluid while at the same time washing the surface 35' of the lens.

In Figs. 26 to 30 is disclosed a modification of the device described above, the instant modification permitting viewing of the sides of a bore hole instead of a bore hole beneath the instrument, or in other words permitting the wall of the bore hole to be viewed at right angles to the axis of the hole. This embodiment is the same as that previously described, except that the structure at the end of the tool below the protective lens 35 is modified.

The modification of the lower end of the television inspection tool as shown in Figs. 26 to 30, is basically composed of a cylindrical case 310, a cylindrical window 312, a sliding cylindrical window cover 314, a conical mirror 316, and a sliding cover operating mechanism

indicated generally by numeral 318. This modified end portion of our instrument is attached to the basic television inspection tool described above just below the protective lens 35.

5 The outside case 310 of the modified end portion hereof including a lens retainer cylinder 320, a housing 322 for a retractable shield actuating cylinder, and an end cap 324 threadably engaging housing 322 at 326. The lens retainer member 320 has its upper end provided with a thread system 328 which mates with threads on the lower end of the body member 66. The lower end of member 320 is provided with a thread 330 to make up with the upper end of housing 322.

10 Positioned axially within lens retainer 320 is a cylindrical light guard 332, having a diameter equal to that of the opaque joint 85 in protective lens 35 at the outside surface thereof. One end of the light guard 332 is placed against the lens 35 at 334, essentially coincident with the opaque joint 85 at the outside of the lens, the other end of the light guard being open at 336. The light guard 332 is maintained in position by three radial support bars 338 (see also Fig. 27).

15 In lens retainer member 320 is positioned the cylindrical window 312. Surrounding window 312 is an open portion 342 in member 320, the end portions 344 and 346 of member 320 adjacent said open portion being connected by three narrow longitudinally extending segments 339, 340 and 341 (see Fig. 27) traversing open portion 342. One of the segments 339 contains a fluid 20 circulating bore 348 which at its upper end 349 connects with a bore 350 in end portion 344 of retainer member 320, bore 350 communicating with bore 70' via the channel 76 of the blocked annulus 74 (see Fig. 31). The window area 312 is fitted with a transparent cylindrical 25 window pane 352 which fits within the segments 339 to 341, and has an inside diameter equal to that of the inside diameter of outer cylinder member 320. A series of spaced longitudinal bores 354 in member 320 also 30 communicate at their upper ends with bore 68' via channel 75 in the blocked annulus 74, and at their lower end with annular space 342 between window 352 and the window cover 314.

35 A mirror 316 is mounted with its axis of revolution 356 coaxial with the axis of lens 35 and the cylinder 40 94 containing the optical lens of the television camera. From the apex 357 of the mirror 316 to a point 358 along its side, the element of the outer surface of the mirror is a straight line, forming a cone as indicated at 359, and below this point to the base of the mirror, 45 the surface is generated by a convex curve, as indicated at 360. The television camera lens in cylinder 94 is focused on and receives light reflected from the conical portion 359 of the mirror, while the convex portion 360 of the mirror 316 functions to reflect light passing through 50 the outer portion 84 of lens 35 and between members 332 and 320, onto the bore hole wall, as indicated by arrows 362. The light which is reflected from the conical portion 359 of the mirror 316 into light guard 332 and portion 82 of lens 35, is received from the side of the 55 bore hole through window 352, as indicated by arrows 363. Light guard 332 is provided to prevent interference between the light rays passing from the outer portion 84 of lens 35 to the convex portion 360 of mirror 316, and the light rays reflected back from the straight 60 portion 359 of mirror 316 to the center portion 82 of lens 35.

65 The protective window 352 and the mirror 316 are held in place by a shoulder 364 in lens retainer member 320 and a shoulder 366 on the upper threaded end of housing 322. All of the space inside of lens retainer cylinder 320 and light guard 332, between the mirror 316 and the protective lens 35, is filled with a suitable transparent liquid such as alcohol, which facilitates viewing 70 of the side of the well bore or casing outside of window 75

352. The fluid pressure within member 320 is maintained at the bore hole pressure by means of a porous plug 368 positioned in the body of member 320.

In order to protect the window 352 from being coated with opaque substances while passing through opaque fluids, the retractable cylindrical shield or cover 314 is provided. The shield 314 is seated and sealed by O rings 370 in spaced grooves formed in the outer surface of member 320, and is made retractable by connecting it to a lift arm 372 which is connected to the piston rod 374 of the hydraulic cylinder assembly 318. The space 342 between the retractable shield 314 and the protective window 352 can be filled with a transparent washing fluid. This is accomplished by means of the bores 354 which at their upper ends are connected via bore 68' to the lens washing tube 115 of the tool.

The cylindrical housing 322 is provided with two diametrically aligned guide slots 376 (see Fig. 28). The guide slots allow the lift arm 372 to pass through said housing to connect with the retractable shield 314. The piston rod 374 to which the lift arm 372 is connected, is in turn connected to a piston 378 positioned in a hydraulic cylinder 379 located within cylinder 322, piston 378 having a sealing ring 380. The lower end of the hydraulic cylinder 379 is connected to a base member 382 attached by means of a screw 384 to a support 386 which in turn is connected as by welding at 388 to the inside surface at the lower end of the cylindrical housing 322. A bore 390 in base member 382 connects the hydraulic cylinder 379 via a vent 392 with the annular space 391 between the outer cylinder 322 and hydraulic cylinder 379. Hence the lower side 393 of piston 378 is subject to the well bore pressure via slots 376, space 391, and bore 390, while the other side 394 of piston 378 is connected via elbow 395, line 396, fitting 396' and fluid annulus 397, to the bore 348. The retractable shield 314 is maintained in the closed position shown in Fig. 26 by means of a spring 398 disposed about piston rod 374, the spring abutting the upper end 397' of hydraulic cylinder 379 and the lower side 397" of lift arm 372, urging the lift arm upward.

In order to retract the shield 314 to view a side of the well bore, piston 178 of hydraulic cylinder 38 is actuated downward as described above, causing a positive fluid pressure with respect to bore hole pressure to be exerted through line 116, bores 70', 350 and 348, and line 396 to the upper side 394 of the piston 378 in the lower hydraulic cylinder 379. This positive pressure will overcome the tension of spring 398 and the well bore pressure exerted against the lower side 393 piston 378, causing piston 378 to be displaced downward and retracting shield 314. This uncovers the protective window 352 for viewing the side of the bore hole. When the positive pressure is released by actuating piston 178 of hydraulic cylinder 38 in the opposite direction, i.e. upward as described above, the spring 398 urges the shield 314 again into closed position to cover the window 352. This upward movement of piston 178 forces wash fluid out of chamber 300 of the hydraulic cylinder 38, through tube 115, bores 68' and 354, and into space 342 between shield 314 and window 352, to fill said space with washing fluid and to thus clean the outside of the window pane 352.

It will be noted that in order to properly remove opaque fluids from space 342 between window 352 and the shield 314, piston 178 of the hydraulic cylinder 38 is actuated by means of the above noted cycle timer to a point say about 2 inches below the top of the cylinder. At this position of the piston it will be seen that the upper end of shield 314 is just below its closed position, leaving a relatively small opening between the top of the shield 314 and the adjacent end of body shell 320. The piston can then be reciprocated up and down over a distance of about 1 inch to force jets of washing fluid through bores 354 downwardly into the top of

space 342, and resulting in a washing of the window 352 and a forcing of the opaque fluid downwardly and then upwardly in space 342 adjacent the inner surface of shield 314 and out of the space provided by the opening adjacent the top of the partially retracted shield 314, into the well bore.

When the opaque fluid in space 342 has been substantially replaced by clear washing fluid, the motor is actuated to force the piston 178 to the top of the hydraulic cylinder 38, permitting the shield 314 to assume its completely closed position as shown in Fig. 26, and entrapping a substantially clear bubble of liquid within space 342. Under these conditions the tool can be again raised or lowered to any position in the well bore at which it is desired to view the side of the bore, and the hydraulic piston 178 actuated downwardly to retract the shield 314 for viewing the side of the bore through the clear bubble of washing fluid in space 342.

The embodiment shown in Fig. 26 can be further modified if desired to permit the washing fluid to be introduced into the bottom of space 342 instead of into the top thereof via bores 354, as shown in Fig. 26. This can be accomplished by closing off bores 354, and by connecting bore 68' with a plurality of bores passing downwardly through the retainer cylinder 320 and thence through the longitudinally extending segments 340 and 341 (see Fig. 27) positioned across the window 352, and thence further conducting the fluid from the bottom of such bores through cylinder 320 adjacent the bottom of space 342 and communicating with the bottom of space 342. In this manner, washing fluid will be discharged in the form of jets upwardly from the bottom of space 342, forcing the opaque fluid in said space upwardly into the top of space 342 and out of the opening provided between the upper end of shield 314 and the adjacent lower end of retainer cylinder 320, when the shield 314 is in retracted or partially retracted position. Simultaneously with this action, the motion of the washing fluid passing upwardly in the space 342 adjacent the window 352 will wash the surface of the window free of any opaque particles deposited thereon.

From the foregoing, it is seen that there is provided, according to the invention, a tool which enables remote instantaneous viewing of a well bore or casing to obtain a quick, exact picture of the bore or the side walls thereof at any depth of the bore hole. The tool can be operated for long periods in the well, and numerous areas of the bore viewed without the necessity of withdrawing the device numerous times, e.g. to remove camera film from the camera and reload it, a disadvantage of those known devices employing such camera means. The invention tool preferably embodies a commercially available closed circuit transmitting and receiving television system adapted for use in the device hereof and under the conditions encountered in well bores. A protective lens system is provided to enable scanning of the well bore while protecting the television system from contamination with well bore fluids. The protective lens can be washed by a hydraulic washing system actuated from the well surface, and the protective lens protected from deposition thereon of opaque substances contained in well bore fluids through which the tool passes, by means such as a diaphragm or other type closure, also actuatable from a remote point at the surface of the well. Means for efficient lighting of the well bore is also provided, as is means for cooling the television system to permit proper operation thereof at the high temperatures encountered in well bores. The device is compact and rugged, yet reliable in operation despite the employment of sensitive electronic components contained in the television system.

While we have shown and described above the use of camera means in conjunction with a television system for pictorially viewing the interior of a well bore at a station at the surface of the well while the tool is still in the well bore, and this is our preferred embodiment,

it will be understood that camera means other than a television camera can be employed in combination with the other features of our device. Thus, a still or movie camera containing photographic film can be used with electric leads connected through cable 44 between the camera and a control mechanism at the surface, for operating the shutter and camera drive from the surface of the well. The types of cameras which can be employed for our purpose can be readily chosen by those skilled in this art.

While we have described a particular embodiment of our invention for the purpose of illustration, it should be understood that various modifications and adaptations thereof may be made within the spirit of the invention as set forth in the appended claims.

We claim:

1. A bore hole inspection tool which comprises a case containing therein camera means, a protective lens for said camera means, a closure spaced from said protective lens away from said camera means, means for actuating said closure to open and close the same repeatedly during traverse of the tool in a well bore, said closure in its closed position forming a confined chamber located between said closure and said protective lens in said case, a receptacle adapted to contain a fluid, conduit means for conducting said fluid to said chamber, means for forcing said fluid from said receptacle through said conduit means to said chamber, and means for raising and lowering said case in a bore hole.

2. A bore hole inspection tool which comprises a case containing therein a television camera, a closed circuit television system for viewing an image received by said camera, a protective lens for said camera, said lens having a diameter substantially equal to the inner diameter of said case and closing off the interior of said case above said lens, a closure spaced from said protective lens away from said camera, means for actuating said closure to open and close the same repeatedly during traverse of the tool in a well bore, said closure in its closed position forming a confined chamber located between said closure and said protective lens in said case, a receptacle adapted to contain a fluid, conduit means for conducting said fluid to said chamber, means for forcing said fluid from said receptacle through said conduit means to said chamber, and means for raising and lowering said case in a bore hole.

3. A bore hole inspection tool which comprises a case containing therein a television camera, a closed circuit television system for viewing an image received by said camera, said camera and television system being positioned in a housing in said case, means for cooling said housing and the contents thereof, said cooling means including a container positioned in the space between said housing and said case, said container including a cooling medium, a protective lens for said camera, a closure spaced from said protective lens away from said camera, means for actuating said closure to open and close the same repeatedly during traverse of the tool in a well bore, said closure in its closed position forming a confined chamber located between said closure and said protective lens in said case, a receptacle adapted to contain a washing fluid, conduit means for conducting said fluid to said chamber, means for forcing said fluid from said receptacle through said conduit means to said chamber, and means for raising and lowering said case in a bore hole.

4. A bore hole inspection tool which comprises an elongated case, said case including a housing mounted near the lower end of said case, camera means positioned in said housing, a protective lens mounted below said camera means in said case and closing off a substantial portion of the interior of said case above said lens, a flexible diaphragm connected to the lower end of said case below said protective lens, said diaphragm being spaced from said lens, a reservoir in said case adapted

5 to contain a liquid, means for opening and closing said diaphragm repeatedly during traverse of the tool in a well bore, said means including means for conducting liquid under pressure from said reservoir to said diaphragm and expanding said diaphragm to close off the bottom of said case and means to withdraw said liquid into said reservoir to contract said diaphragm, means to conduct liquid from within said case into the space directly in front of said protective lens, means preventing return flow of liquid from said space into said case, and means for raising and lowering said case in a bore hole.

10 5. A bore hole inspection tool which comprises an elongated case, said case including a housing mounted near the lower end of said case, camera means positioned in said housing, a protective lens mounted below said camera means in said case and closing off a substantial portion of the interior of said case above said lens, a flexible diaphragm connected to the lower end of said case below said protective lens, said diaphragm being spaced from said lens, a hydraulic chamber positioned in the closed off interior portion of said case above said housing, a piston in said chamber, a first conduit connecting a portion of said hydraulic chamber on one side of said piston with said diaphragm for conducting liquid under pressure to said diaphragm and expanding said diaphragm to close off the bottom of said case, said liquid returning to said portion of said chamber, a second conduit connecting another portion of said hydraulic chamber on the other side of said piston with the space directly in front of said protective lens to direct fluid into said space for washing said protective lens, valve means in said second conduit preventing return flow of fluid therein from the discharge end of said second conduit back to said hydraulic chamber, means for actuating said piston, and means for raising and lowering said case in a bore hole.

15 6. A bore hole inspection tool which comprises an elongated case, said case including a first housing mounted near the lower end of said case, said housing being spaced from the inner wall of said case, camera means positioned in said first housing, a container positioned in the annular space between said first housing and said case, said container including a cooling medium to cool said first housing and the contents thereof, a protective lens mounted below said camera in said case and closing off a substantial portion of the interior of said case above said lens, a lamp housing positioned adjacent said first housing and above said protective lens, a lamp in said lamp housing, said lamp being adapted to transmit light through said lens, a flexible diaphragm connected to the lower end of said case below said protective lens, said diaphragm being spaced from said lens, a reservoir in said case adapted to contain a liquid, means for opening and closing said diaphragm repeatedly during traverse of the tool in a well bore, said means including means for conducting liquid under pressure from said reservoir to said diaphragm and expanding said diaphragm to close off the bottom of said case and to withdraw liquid into said case to contract said diaphragm, and means for raising and lowering said case in a bore hole.

20 7. A bore hole inspection tool which comprises an elongated case, said case including a first housing mounted near the lower end of said case, said housing being spaced from the inner wall of said case, a television camera and a closed television circuit connected to said camera, said camera and circuit being positioned in said first housing, a container positioned in the annular space between said first housing and said case, said container including a cooling medium to cool said first housing and the contents thereof, a protective lens mounted below said camera in said case and closing off a substantial portion of the interior of said case above said lens, a lamp housing positioned adjacent said first housing and above said protective lens, a ring shaped lamp in said lamp housing, said lamp being adapted to transmit light

through said lens, a flexible diaphragm connected to the lower end of said case below said protective lens, said diaphragm being spaced from said lens a reservoir in said case adapted to contain a liquid, means for opening and closing said diaphragm repeatedly during traverse of the tool in a well bore, said means including means for conducting liquid under pressure from said reservoir to said diaphragm and expanding said diaphragm to close off the bottom of said reservoir and means to withdraw liquid into said case to contract said diaphragm, means to conduct liquid from within said case into the space directly in front of said protective lens, means preventing return flow of liquid from said space into said case, and means for raising and lowering said case in a bore hole.

8. A bore hole inspection tool which comprises an elongated case, said case including a first housing mounted near the lower end of said case, said housing being spaced from the inner wall of said case, a television camera and a closed television circuit connected to said camera, said camera and circuit being positioned in said first housing, a container positioned in the annular space between said first housing and said case, said container including a cooling medium to cool said first housing and the contents thereof, a protective lens mounted below said camera in said case and closing off a substantial portion of the interior of said case above said lens, a lamp housing positioned adjacent said first housing and above said protective lens, a lamp in said lamp housing, said lamp being adapted to transmit light through said lens, a flexible diaphragm connected to the lower end of said case below said protective lens, said diaphragm being spaced from said lens, a hydraulic chamber positioned in the closed off interior portion of said case above said first housing, a piston in said chamber, a first conduit connecting a portion of said piston with said hydraulic chamber on one side of said piston with said diaphragm, for conducting liquid under pressure to said diaphragm and expanding said diaphragm to close off the bottom of said case, said liquid returning to said portion of said chamber, a second conduit connecting another portion of said hydraulic chamber on the other side of said piston with the space directly in front of said protective lens to direct liquid into said space for washing said protective lens, valve means in said second conduit preventing return flow of liquid therein from the discharge end of said second conduit back to said hydraulic chamber, means for actuating said piston, and means for raising and lowering said case in a bore hole.

9. A bore hole inspection tool which comprises an elongated case, said case including a first housing mounted near the lower end of said case, a camera positioned in said first housing, a protective lens mounted below said camera in said case, and closing off a substantial portion of the interior of said case above said lens, said lens being composed of a central downwardly flared truncated conical inner portion and an annular outer portion mating with said inner portion, an opaque coating at the interface between said inner and outer lens portions, said camera being in axial alignment with and receiving light substantially only from the central inner portion of said lens, a lamp housing positioned adjacent said first housing and above said protective lens, an annularly shaped lamp in said lamp housing, said lamp being in alignment with the outer portion of said lens and transmitting light substantially only through said outer lens portion, and means for raising and lowering said case in a bore hole.

10. A bore hole inspection tool which comprises an elongated case, said case including a first housing mounted near the lower end of said case, said housing being spaced from the inner wall of said case, a television camera and a closed television circuit connected to said camera, said camera and circuit being positioned in said first housing, a container positioned in the annular space between said first housing and said case, said container

including a cooling medium to cool said first housing and the contents thereof, a protective lens mounted below said camera in said case and closing off a substantial portion of the interior of said case above said lens, said lens being composed of a central downwardly flared truncated conical inner portion and an annular outer portion mating with said inner portion, an opaque coating at the interface between said inner and outer lens portions, said camera being in axial alignment with and receiving light substantially only from the central inner portion of said lens, a lamp housing positioned adjacent said first housing and above said protective lens, an annularly shaped lamp in said lamp housing, said lamp being in alignment with the outer portion of said lens and transmitting light substantially only through said outer lens portion, and means for raising and lowering said case in a bore hole.

11. A bore hole inspection tool which comprises an elongated case, said case including a first housing mounted near the lower end of said case, said housing being spaced from the inner wall of said case, camera means positioned in said first housing, a container positioned in the annular space between said first housing and said case, said container including a cooling medium to cool said first housing and the contents thereof, a protective lens mounted below said camera in said case and closing off a substantial portion of the interior of said case above said lens, said lens being composed of a central downwardly flared truncated conical inner portion and an annular outer portion mating with said inner portion, an opaque coating at the interface between said inner and outer lens portions, said camera means being in axial alignment with and receiving light substantially only from the central inner portion of said lens, a lamp housing positioned adjacent said first housing and above said protective lens, an annularly shaped lamp in said lamp housing, said lamp being in alignment with the outer portion of said lens and transmitting light substantially only through said outer lens portion, a flexible diaphragm connected to the lower end of said case below said protective lens, said diaphragm being spaced from said lens, means for opening and closing said diaphragm, said means including means for conducting liquid under pressure from said case to said diaphragm and expanding said diaphragm to close off the bottom of said case and to withdraw said liquid into said case to contract said diaphragm, means to conduct a fluid from said case into the space directly in front of said protective lens, means preventing return flow of fluid from said space into said case, and means for raising and lowering said case in a bore hole.

12. A bore hole inspection tool which comprises an elongated case, said case including a first housing mounted near the lower end of said case, said housing being spaced from the inner wall of said case, a television camera and a closed television circuit connected to said camera, said camera and circuit being positioned in said first housing, a container positioned in the annular space between said first housing and said case, said container including a cooling medium to cool said first housing and the contents thereof, a protective lens mounted below said camera in said case and closing off a substantial portion of the interior of said case above said lens, said lens being composed of a central downwardly flared truncated conical inner portion and an annular outer portion mating with said inner portion, an opaque coating at the interface between said inner and outer lens portions, said camera being in axial alignment with and receiving light substantially only from the central inner portion of said lens, a lamp housing positioned adjacent said first housing and above said protective lens, an annularly shaped lamp in said lamp housing, said lamp being in alignment with the outer portion of said lens and transmitting light substantially only through said outer lens portion, a flexible diaphragm connected to the lower end of said case below said protective lens, said diaphragm being spaced

from said lens, a hydraulic chamber positioned in the closed-off interior portion of said case above said first housing, a piston in said chamber, a first conduit connecting a portion of said hydraulic chamber on one side of said piston with said diaphragm, for conducting liquid under pressure to said diaphragm and expanding said diaphragm to close off the bottom of said case, said liquid returning to said portion of said chamber, a second conduit connecting another portion of said hydraulic chamber on the other side of said piston with the space directly in front of said protective lens to direct fluid into said space for washing said protective lens, valve means in said second conduit preventing return flow of fluid therein from the discharge end of said second conduit back to said hydraulic chamber, means for actuating said piston, and means for raising and lowering said case in a bore hole.

13. A bore hole inspection tool which comprises an elongated case, said case including a housing mounted near the lower end of said case, camera means positioned in said housing, a protective lens mounted below said camera in said case and closing off a substantial portion of the interior of said case above said lens, a flexible diaphragm connected to the lower end of said case below said protective lens, said diaphragm being spaced from said lens, a hydraulic chamber positioned in the closed off interior portion of said case above said housing, a piston in said chamber, a first conduit connecting a portion of said hydraulic chamber on one side of said piston with said diaphragm, for conducting liquid under pressure to said diaphragm and expanding said diaphragm to close off the bottom of said case, said liquid returning to said portion of said chamber, a second conduit connecting another portion of said hydraulic chamber on the other side of said piston with the space directly in front of said protective lens, to direct fluid into said space for washing said protective lens, valve means in said second conduit preventing return flow of fluid therein from the discharge end of said second conduit back to said hydraulic chamber, means for actuating said piston, a fluid reservoir chamber positioned in said case above said hydraulic chamber, a freely sliding piston in said reservoir chamber, a third conduit connecting said reservoir chamber with said another portion of said hydraulic chamber, valve means in said third conduit preventing return flow of liquid in said third conduit from said hydraulic chamber to said reservoir chamber, an inlet for liquid in said case, a fourth conduit connecting said inlet with said reservoir chamber, a closure for said inlet, and means for raising and lowering the case in a well bore.

14. A bore hole inspection tool which comprises an elongated case, said case including a first housing mounted near the lower end of said case, said housing being spaced from the inner wall of said case, a television camera and a closed television circuit connected to said camera, said camera and circuit being positioned in said first housing, a container positioned in the space between said first housing and said case, said container including a cooling medium to cool said first housing and the contents thereof, a protective lens mounted below said camera in said case and closing off a substantial portion of the interior of said case above said lens, a lamp housing positioned adjacent said first housing and above said protective lens, a lamp in said lamp housing, said lamp being adapted to transmit light through said lens, a flexible diaphragm connected to the lower end of said case below said protective lens, said diaphragm being spaced from said lens, a hydraulic chamber positioned in the closed off exterior portion of said case above said first housing, a piston in said chamber, a first conduit connecting a portion of said hydraulic chamber on one side of said piston with said diaphragm, for conducting liquid under pressure to said diaphragm and expanding said diaphragm to close off the bottom of said case,

said liquid returning to said portion of said chamber, a second conduit connecting another portion of said hydraulic chamber on the other side of said piston with the space directly in front of said protective lens, to direct fluid into said space for washing said protective lens, valve means in said second conduit preventing return flow of fluid therein from the discharge end of said second conduit back to said hydraulic chamber, means for actuating said piston, a fluid reservoir chamber positioned in said case above said hydraulic chamber, a freely sliding piston in said reservoir chamber, a third conduit connecting said reservoir chamber with said another portion of said hydraulic chamber, valve means in said third conduit preventing return flow of liquid in said third conduit from said hydraulic chamber to said reservoir chamber, an inlet for liquid in said case, a fourth conduit connecting said inlet with said reservoir chamber, a closure for said inlet, and means for raising and lowering the case in a well bore.

15. A bore hole inspection tool which comprises an elongated case, said case including a first housing mounted near the lower end of said case, said housing being spaced from the inner wall of said case, camera means positioned in said first housing, a container positioned in the annular space between said first housing and said case, said container including a cooling medium to cool said first housing and the contents thereof, a protective lens mounted below said camera means in said case and closing off a substantial portion of the interior of said case above said lens, said lens being composed of a central downwardly flared truncated conical inner portion and an annular outer portion mating with said inner portion, an opaque coating at the interface between said inner and outer lens portions, said camera being in axial alignment with and receiving light substantially only from the central inner portion of said lens, a lamp housing positioned adjacent said first housing and above said protective lens, an annularly shaped lamp in said lamp housing, said lamp being in alignment with the outer portion of said lens and transmitting light substantially only through said outer lens portion, a flexible diaphragm connected to the lower end of said case below said protective lens, said diaphragm being spaced from said lens, a hydraulic chamber positioned in the closed off interior portion of said case above said first housing, a piston in said chamber, a first conduit connecting a portion of said hydraulic chamber on one side of said piston with said diaphragm, for conducting liquid under pressure to said diaphragm and expanding said diaphragm to close off the bottom of said case, said liquid returning to said portion of said chamber, a second conduit connecting another portion of said hydraulic chamber on the other side of said piston with the space directly in front of said protective lens, to direct fluid into said space for washing said protective lens, valve means in said second conduit preventing return flow of fluid therein from the discharge end of said second conduit back to said hydraulic chamber, a piston rod connected to said piston, and a motor for actuating said piston rod, said motor being mounted in said case above said hydraulic chamber.

16. A bore hole inspection tool which comprises an elongated cylindrical case, said case being composed of a plurality of sections threadably engaged with each other, said case including a first housing mounted near the lower end of said case, said housing being spaced from the inner wall of said case, a television camera and a closed television circuit connected to said camera, said camera and circuit being positioned in said first housing, a container positioned in the annular space between said first housing and said case, said container including a cooling medium to cool said first housing and the contents thereof, a cylindrical protective lens mounted below said camera in said case and closing off a substantial portion of the interior of said case above said lens, said lens

being composed of a central downwardly flared truncated conical inner portion and an annular outer portion mating with said inner portion, an opaque coating at the interface between said inner and outer lens portions, said camera being in axial alignment with and receiving light substantially only from the central inner portion of said lens, a lamp housing positioned adjacent said first housing and above said protective lens, an annular doughnut-shaped lamp in said lamp housing, said lamp being in alignment with the outer portion of said lens and transmitting light substantially only through said outer lens portion, said lamp housing abutting the back of said protective lens, and sealing said lamp off from the interior of said case above said lamp housing, a cylindrically shaped flexible diaphragm connected to the lower end of said case below said protective lens, forming a closed annular space between said diaphragm and the inner wall of said case, said diaphragm being spaced from said lens, a hydraulic cylinder positioned in the closed off interior portion of said case above said first housing, a piston in said cylinder, a first conduit connecting the bottom of said hydraulic cylinder on one side of said piston with the annular space between said diaphragm and the inner wall of said case for conducting liquid under pressure to said space for expanding said diaphragm to close off the bottom of said case, a second conduit connecting the top of said hydraulic cylinder with the space directly in front of said protective lens, the end of said conduit being positioned to direct fluid to be discharged therefrom over the front surface of said protective lens, a check valve in said second conduit preventing return flow of fluid therein from the discharge end of said second conduit back to the top of said hydraulic cylinder, a piston rod connected to said piston, a motor for actuating said piston rod, said motor being mounted in said case above said hydraulic cylinder, a connection between said motor and said piston rod, a fluid reservoir positioned in said case above said motor, a freely sliding piston in said reservoir, a third conduit connecting the bottom of said reservoir with the top of said hydraulic cylinder, a check valve in said third conduit preventing return flow of liquid in said third conduit from said hydraulic cylinder to said reservoir, a first inlet in said case, a fourth conduit connecting said inlet with the bottom of said reservoir, a closure for said inlet, a second inlet in said case, a fifth conduit connecting said second inlet with the top of said reservoir, a vent plug in said second inlet permitting fluid flow from the exterior of said case through said fifth conduit to said reservoir, a cable connected to the top of said case for raising and lowering the case in a well bore, said cable containing electrical leads to said lamp, to said television circuit and to said motor for actuation thereof, whereby an image of the bore hole received by said camera is transmitted to a television picture tube remote from said tool.

17. A bore hole inspection tool which comprises an elongated case, said case including a housing mounted near the lower end of said case, camera means positioned in said housing, a protective lens mounted below said camera in said case and closing off a substantial portion of the interior of said case above said lens, an elongated light guard positioned axially in said case below said protective lens, a connection between said light guard and said case, the ends of said light guard being open, one end of said light guard being positioned closely adjacent the front surface of said lens, a transparent window forming a portion of the wall of said case below said light guard, a conical mirror positioned in said case adjacent said window and spaced from the lower end of said light guard, said mirror being adapted to transmit light to and to receive light from said window, a retractable shield covering said window on the outside of said case, said shield being spaced from said window to form a closed annular space, means for retracting said

shield from said window, means for actuating said shield retracting means, a chamber positioned in said case, a conduit connecting said chamber with the annular space between said window and said retractable shield for conducting washing fluid to said window, and means for raising and lowering said case in said bore hole.

18. A bore hole inspection tool which comprises an elongated case, said case including a housing mounted near the lower end of said case, camera means positioned in said housing, a protective lens mounted below said camera in said case and closing off a substantial portion of the interior of said case above said lens, an elongated light guard positioned axially in said case below said protective lens, a connection between said light guard and said case, the ends of said light guard being open, one end of said light guard being positioned closely adjacent the front surface of said lens, a transparent window forming a portion of the wall of said case below said light guard, a conical mirror positioned in said case adjacent said window and spaced from the lower end of said light guard, said mirror being adapted to transmit light to and to receive light from said window, a retractable shield covering said window on the outside of said case, said shield being spaced from said window to form a closed annular space, an actuating cylinder, a piston in said cylinder, a connection between said piston and said retractable shield, a hydraulic chamber positioned in the closed off interior portion of said case above said housing, a piston in said chamber, a first conduit connecting a portion of said hydraulic chamber on one side of said last mentioned piston with said actuating cylinder for conducting liquid under pressure to said actuating cylinder for operating said retractable shield, a second conduit connecting another portion of said hydraulic chamber on the other side of said piston with the annular space between said window and said retractable shield for conducting washing fluid to said window, means for actuating said last mentioned piston, and means for raising and lowering said case in said bore hole.

19. A bore hole inspection tool which comprises an elongated case, said case including a first housing mounted near the lower end of said case, said housing being spaced from the inner wall of said case, a television camera and a closed television circuit connected to said camera, said camera and circuit being positioned in said first housing, a container positioned in the space between said first housing and said case, said container including a cooling medium to cool said first housing and the contents thereof, a protective lens mounted below said camera in said case and closing off a substantial portion of the interior of said case above said lens, a lamp housing positioned adjacent said first housing and above said protective lens, a lamp in said lamp housing, said lamp being adapted to transmit light through said lens, an elongated light guard positioned axially in said case below said protective lens, a connection between said light guard and said case, the ends of said light guard being open, one end of said light guard being positioned closely adjacent the front surface of said lens, a transparent window forming a portion of the wall of said case below said light guard, a conical mirror positioned in said case adjacent said window and spaced from the lower end of said light guard, said mirror being adapted to transmit light to and to receive light from said window, a retractable shield covering said window on the outside of said case, said shield being spaced from said window to form a closed annular space, an actuating cylinder, a piston in said cylinder, a rod connected to said piston, a connection between said piston rod and said retractable shield, a hydraulic chamber positioned in the closed off interior portion of said case above said housing, a piston in said chamber, a first conduit connecting a portion of said hydraulic chamber on one side of said last mentioned piston with said actuating cylinder for conducting liquid

under pressure to said actuating cylinder for operating said retractable shield, a second conduit connecting another portion of said hydraulic chamber on the other side of said piston with the annular space between said window and said retractable shield for conducting washing fluid to said window, valve means in said second conduit preventing return flow of fluid therein from said annular space back to said hydraulic chamber, a piston rod connected to said last mentioned piston, a motor for actuating said last mentioned piston rod, said motor being mounted in said case above said hydraulic chamber, and a cable for raising and lowering said case in said bore hole.

20. A bore hole inspection tool which comprises an elongated case, said case including a first housing mounted near the lower end of said case, said housing being spaced from the inner wall of said case, camera means positioned in said first housing, a container positioned in the annular space between said first housing and said case, said container including a cooling medium to cool said first housing and the contents thereof, a protective lens mounted below said camera means in said case and closing off a substantial portion of the interior of said case above said lens, said lens being composed of a central downwardly flared truncated conical inner portion and an annular outer portion mating with said inner portion, an opaque coating at the interface between said inner and outer lens portions, said camera being in axial alignment with and receiving light substantially only from the central inner portion of said lens, a lamp housing positioned adjacent said first housing and above said protective lens, an annularly shaped lamp in said lamp housing, said lamp being in alignment with the outer portion of said lens and transmitting light substantially only through said outer portion, an elongated light guard positioned axially in said case below said protective lens, a connection between said light guard and said case, the ends of said light guard being open, one end of said light guard being positioned closely adjacent the front surface of said lens, a transparent window forming a portion of the wall of said case below said light guard, a conical mirror positioned in said case adjacent said window and spaced from the lower end of said light guard, said mirror being adapted to transmit light to and to receive light from said window, a retractable shield covering said window on the outside of said case, said shield being spaced from said window to form a closed annular space, an actuating cylinder, a piston in said cylinder, a rod connected to said piston, a connection between said piston rod and said retractable shield, a hydraulic chamber positioned in the closed off interior portion of said case above said housing, a piston in said chamber, a first conduit connecting a portion of said hydraulic chamber on one side of said last mentioned piston with said actuating cylinder for conducting liquid under pressure to said actuating cylinder for operating said retractable shield, a second conduit connecting another portion of said hydraulic chamber on the other side of said piston with the annular space between said window and said retractable shield for conducting washing fluid to said window, valve means in said second conduit preventing return flow of fluid therein from said annular space back to said hydraulic chamber, a piston rod connected to said last mentioned piston, a motor for actuating said last mentioned piston rod, said motor being mounted in said case above said hydraulic chamber, and a cable for raising and lowering said case in said bore hole.

21. A bore hole inspection tool which comprises an elongated case, said case including a first housing mounted near the lower end of said case, said housing being spaced from the inner wall of said case, a television camera and a closed television circuit connected to said camera, said camera and circuit being positioned in said first housing, a container positioned in the annular

space between said first housing and said case, said container including a cooling medium to cool said first housing and the contents thereof, a protective lens mounted below said camera in said case and closing off a substantial portion of the interior of said case above said lens, said lens being composed of a central downwardly flared truncated conical inner portion and an annular outer portion mating with said inner portion, an opaque coating at the interface between said inner and outer lens portions, said camera being in axial alignment with and receiving light substantially only from the central inner portion of said lens, a lamp housing positioned adjacent said first housing and above said protective lens, an annularly shaped lamp in said lamp housing, said lamp being in alignment with the outer portion of said lens and transmitting light substantially only through said outer portion, an elongated light guard positioned axially in said case below said protective lens, a connection between said light guard and said case, the ends of said light guard being open, one end of said light guard being positioned closely adjacent the front surface of said lens, a transparent window forming a portion of the wall of said case below said light guard, a conical mirror positioned in said case adjacent said window and spaced from the lower end of said light guard, said mirror being adapted to transmit light to and to receive light from said window, a retractable shield covering said window on the outside of said case, said shield being spaced from said window to form a closed annular space, an actuating cylinder, a piston in said cylinder, a rod connected to said piston, a connection between said piston rod and said retractable shield, a hydraulic chamber positioned in the closed off interior portion of said case above said housing, a piston in said chamber, a first conduit connecting a portion of said hydraulic chamber on one side of said last mentioned piston with said actuating cylinder for conducting liquid under pressure to said actuating cylinder for operating said retractable shield, a second conduit connecting another portion of said hydraulic chamber on the other side of said piston with the annular space between said window and said retractable shield for conducting washing fluid to said window, valve means in said second conduit preventing return flow of fluid therein from said annular space back to said hydraulic chamber, a piston rod connected to said last mentioned piston, a motor for actuating said last mentioned piston rod, said motor being mounted in said case above said hydraulic chamber, a fluid reservoir chamber positioned in said case above said motor, a freely sliding piston in said reservoir chamber, a third conduit connecting said reservoir chamber with said another portion of said hydraulic chamber, valve means in said third conduit preventing return flow of liquid in said third conduit from said hydraulic chamber to said reservoir chamber, an inlet for liquid in said case, a fourth conduit connecting said inlet with said reservoir chamber, a closure for said inlet, and a cable connected to the top of said case for raising and lowering the case in a well bore.

22. A bore hole inspection tool which comprises an elongated cylindrical case, said case being composed of a plurality of sections threadably engaged with each other, said case including a first housing mounted near the lower end of said case, said housing being spaced from the inner wall of said case, a television camera and a closed television circuit connected to said camera, said camera and circuit being positioned in said first housing, a container positioned in the annular space between said first housing and said case, said container including a cooling medium to cool said first housing and the contents thereof, a cylindrical protective lens mounted below said camera in said case, and closing off a substantial portion of the interior of said case above said lens, said lens being composed of a central down-

wardly flared truncated conical inner portion and an annular outer portion mating with said inner portion, an opaque coating at the interface between said inner and outer lens portions, the front lower surface of said lens being convex, said camera being in axial alignment with and receiving light substantially only from the central inner portion of said lens, a lamp housing positioned adjacent said first housing and above said protective lens, an annular doughnut-shaped lamp in said lamp housing, said lamp being in alignment with the outer portion of said lens and transmitting light substantially only through said outer lens portion, said lamp housing abutting the back of said protective lens and sealing said lamp off from the interior of said case above said lamp housing, an elongated cylindrical light guard positioned axially in said case below said protective lens, a connection between said light guard and said case, the ends of said light guard being open, one end of said light guard abutting the front surface of said lens at the circular opaque interface between the inner and outer portions of said lens, a cylindrical transparent window forming a portion of the wall of said case below said light guard, a conical mirror positioned in said case adjacent said window and spaced from the lower end of said light guard, said mirror being adapted to transmit light to and to receive light from said window, the axis of said mirror being on a line with the axis of said protective lens and of said light guard, the apex of said conical mirror being the closest point on said mirror to the lower end of said light guard, the upper portion of the surface of said conical mirror adjacent the apex thereof being straight, the remaining lower portion of said surface being convex, a retractable shield covering said window on the outside of said case, said shield being spaced from said window to form an annular space therein, a lift arm connected to said shield, slots in said case for longitudinal movement of said lift arm and said shield, an actuating cylinder for operation of said lift arm, said cylinder being spaced from the inner wall of said case, a piston in said cylinder, a rod connecting said piston and said lift arm, a spring between said cylinder and said lift arm urging said retractable shield upwards into closed position, a passage connecting the lower end of said actuating cylinder and the space between said cylinder and the inner wall of said case, a filter plug in said case between said protective lens and said conical mirror for equalizing fluid pressure between the outside of the case and the interior of said case between said protective lens and said conical mirror, a hydraulic cylinder positioned in said case above said first housing, a piston in said hydraulic cylinder, a first conduit connecting the bottom of said hydraulic cylinder with the top of said actuating cylinder for conducting liquid under pressure to said actuating cylinder for retracting said shield, a second conduit connecting the top of said hydraulic cylinder with the annular space between said window and said retractable shield for conducting washing fluid to said window, a check valve in said second conduit preventing return flow of fluid therein from said annular space back to the top of said hydraulic cylinder, a piston rod connected to said hydraulic piston, a motor for actuating said piston rod, said motor being mounted in said case above said hydraulic cylinder, a connection between said motor and piston rod, a fluid reservoir positioned in said case above said motor, a freely sliding piston in said reservoir, a third conduit connecting the bottom of said reservoir with the top of said hydraulic cylinder, a check valve in said third conduit preventing return flow of liquid in said third conduit from said hydraulic cylinder to said reservoir, a first inlet in said case, a fourth conduit connecting said inlet with the bottom of said reservoir, a closure for said inlet, a second inlet in said case, a fifth conduit connecting said second inlet with the top of said reservoir, a vent plug in said second inlet permitting fluid flow from the

exterior of said case through said fifth conduit to said reservoir, a cable connected to the top of said case for raising and lowering the case in a well bore, said cable containing electrical leads to said lamp, to said television circuit and to said motor for actuation thereof, whereby an image of the side wall of a bore hole received by said camera is transmitted to a television picture tube remote from said tool.

23. A bore hole inspection tool which comprises a case containing therein camera means, a protective lens for said camera means, a closure spaced from said protective lens away from said camera means, means for actuating said closure to open and close the same while said tool is positioned in a well bore, said closure in its closed position forming a confined chamber between said closure and said protective lens in said case, a receptacle adapted to contain a fluid, conduit means for conducting said fluid to said chamber, means for forcing said fluid from said receptacle through said conduit means to said chamber, said last named means operating in cooperation with said closure actuating means, and means for raising and lowering said case in a bore hole.
24. A bore hole inspection tool which comprises a case containing therein camera means, a protective lens for said camera means, a closure spaced from said protective lens away from said camera means, means for actuating said closure to open and close the same while said tool is positioned in a well bore, said closure in its closed position forming a confined chamber between said closure and said protective lens in said case, a receptacle adapted to contain a fluid, conduit means for conducting said fluid to said chamber, means for forcing said fluid from said receptacle through said conduit means to said chamber, said last named means operating in cooperation with said closure actuating means, said fluid forcing means conducting fluid to said chamber simultaneously with operation of said closure actuating means in a direction to open said closure, and said fluid forcing means being inoperative on operation of said closure actuating means in a direction to close said closure, and means for raising and lowering said case in a bore hole.
25. A bore hole inspection tool which comprises a case containing therein camera means, a protective lens for said camera means, means for illuminating a zone of the well bore located beyond the lowermost extremity of said tool, a closure spaced from said protective lens away from said camera means, means for actuating said closure to open and close the same repeatedly during traverse of the tool in a well bore, said closure in its closed position forming a confined chamber located between said closure and said protective lens in said case, a receptacle adapted to contain a fluid, conduit means for conducting said fluid to said chamber, means for forcing said fluid from said receptacle through said conduit means to said chamber, and means for raising and lowering said case in a bore hole.
